[57] **ABSTRACT**

A garment with a pocket opening either in patch pocket form or otherwise is provided with a secret pocket and flap that is attached either to the upper edge of the main pocket or to the garment or adapted to be inserted through the garment cloth into a pocket within the garment, but at the same time this flap is attached at all times to one side or the other of the pocket and when it is pulled out and allowed to depend from the upper edge of the pocket its own pocket is readily accessible. When the flap and the secret pocket is returned to the main pocket the opening of the flap pocket will lie against one wall of the pocket and closed by the main flap from access by a hand extended into the main pocket. The flap can also be long and its pocket can be extended downwardly beyond the lower end of the pocket and into a pocket on the inner wall of the garment cloth, the garment cloth having been provided with an opening through which the flap and its pocket can be extended.

FIG. 21.

**GARMENT WITH A REMOVABLE SECRET
POCKET FLAP**

This invention relates to a secret pocket provided upon a flap extendable into and out of the main pocket opening.

It is a principle object of the present invention to provide a secret pocket which can be readily accessible to include in the secret pocket any articles such as a purse or billfold, but upon the secret pocket being reinserted into the main pocket opening the secret pocket is closed by the flap itself so that upon the hand of an intruder being extended into the main pocket there is no access to the secret flap pocket and the intruder will not readily find the purse or billfold that lies within the secret pocket.

It is another object of the invention to provide a secret pocket contained on the flap that can be taken out of or extended into a main pocket from its upper edge opening and wherein the flap can be made sufficiently long to extend to the bottom of a deep pocket opening or even through a wall in the garment cloth to lie within the coat when drawn into the main pocket opening.

It is a further object of the invention to provide a secret flap pocket that is inaccessible to an intruder in which access to the secret pocket is not easily made known by one observing something being applied to the secret pocket, the secret pocket, the secret pocket by color appearing as an ordinary pocket on a coat but when installed inside of the pocket opening the articles contained therein are inaccessible to an ordinary intruder and wherein if the secret pocket and the flap is withdrawn, the wearer of the coat is readily informed of the attempt to rob the wearer of the coat of her purse or billfold or any articles of value.

Other objects of the invention are to provide a secret pocket construction which is made of a minimum number of pieces, easy to install upon the pocket opening, has easy access for one who knows the construction, can be installed upon an ordinary pocket opening by simply attaching its flap end to the upper edge of the pocket, light in weight, effective and efficient in use.

For a better understanding of the invention, reference may be had to the following detailed construction, taken in connection with the accompanying drawings, in which:

FIG. 1 is a fragmentary front elevational view of one side panel of a top coat bearing the pocket structure of the present invention.

FIG. 2 is an enlarged fragmentary front elevational view of the pocket structure, the safety pocket lifted out from the top edge of the pocket.

FIG. 3 is a vertical sectional view of the lifted out safety pocket as viewed on line 3-3 of FIG. 2.

FIG. 4 is a vertical sectional view similar to FIG. 3 with the safety pocket flap partly folded up to effect closing of its opening prior to being inserted into the coat pocket.

FIG. 5 is a vertical sectional view similar to FIG. 4 after the folded up safety pocket and flap has been lowered into the outer pocket of the top coat.

FIG. 6 is an enlarged sectional view of a slightly modified form of construction wherein the top coat pocket is of a length to include the length of the flap and the safety pocket so that the safety pocket will lie

in the bottom of the pocket with the wallet contents and the hand when inserted would have to be extended the full depth of the pocket in order to remove the safety pocket and to greater extend the forms of the invention shown in FIGS. 4 and 5.

FIG. 7 is a vertical sectional view of a modified construction wherein the secret pocket extends into a further pocket and extended through an opening in the upper edge of the outer pocket inwardly thereof continues into a pocket provided on the inside wall of a coat, a flap being extended over the opening in the top edge of the outer pocket.

FIG. 8 is a vertical sectional view of the secret pocket flap being placed into an opening in the inner wall of the outer pocket and covered by a flap and snap.

FIG. 9 is a vertical sectional view of a still further form of the invention wherein the secret pocket is extended into a supplementary pocket disposed outwardly of the outer pocket and closed by a button flap.

FIG. 10 is a vertical sectional view of a still further form of the invention wherein the secret pocket is disposed behind the wall of the coat and closed by a slide fastener device located at the upper edge of the outer pocket and on the inner wall of the coat.

FIG. 11 is a vertical sectional view of a form of the invention shown in FIG. 10 but with the secret pocket drawn through the slide fastener opening to be accessible for the insertion of a wallet or other article and brought outwardly over the upper edge of the outer pocket.

FIG. 12 is a side elevational view of a trouser having a side pocket and with the secret pocket of the present invention withdrawn from the side pocket.

FIG. 13 is a side elevational view of a trouser pocket with a secret pocket having been inserted thereinto.

FIG. 14 is a front elevational view of a suit coat having a secret pocket flap pulled outwardly from a top breast pocket.

FIG. 15 is a front elevational view of a suit coat after the secret pocket and flap has been returned to the breast pocket.

FIG. 16 is a front perspective view of a scarf with a secret pocket of the present invention drawn from a pocket in the end of the scarf.

FIG. 17 is a similar front perspective view as shown in FIG. 16 and with the secret pocket and its flap rolled up and extended into the main pocket of the scarf.

FIG. 18 is a perspective view of a money belt having a pocket and with the secret pocket and flap withdrawn therefrom.

FIG. 19 is a perspective view similar to FIG. 18, but with the secret pocket rolled up and extended into the money belt pocket.

FIG. 20 is a front elevational view of one side of a coat having a breast pocket wherein the flap and the secret pocket is of such length as to accommodate spectacles.

FIG. 21 is a view similar to FIG. 20, but with the secret pocket and flap folded into the breast pocket with the spectacles.

Referring now, particularly to FIGS. 1 to 5, there is shown a top or overcoat 25 having a large side pocket 26 in the form of a patch pocket on the side of the coat stitched at the bottom at 27 and this stitching extends up the sides to secure the pocket 26 to the outer sur-

face of the coat 25. This pocket 26 has an upper edge and according to the present invention there is sewn to this upper edge at 28 a long flap 29, the sewing being with the upper edge of the flap 29 lying within and over top edge 31 of the pocket 26. This flap has a length when pulled out of the pocket 26 that is nearly twice the depth of the regular pocket 26 and has a secret pocket 32 open at 33 about halfway down the length of the extended flap 29 so as to receive an article such as a purse 34, this pocket is effected by stitching 35 and is closed at the bottom and sides as with any patch pocket.

When the flap 29 is withdrawn from the pocket and allowed to be extended therefrom access is had to the opening 33 into the secret pocket 32 and the pocket 32 will appear somewhat as the pocket 26, but is not actually the same pocket or a part thereof.

The flap 29 is returned with the article to the main pocket 26 by folding upwardly as shown in FIG. 4 and thereafter taking the pocket with the article and flap and dropping it into the upper opening of the regular patch pocket 26 as best seen in FIG. 5. If anyone inserts a hand into the pocket 26 immediate access is not had to the purse 34 and by the time that the purse was removed along with the long flap 29 the wearer of the coat will be alerted to anyone attempting to rob his pocket of the contents. As to how to gain access thereto it would not readily be apparent to one who did not have this type of pocket on his own garment.

In FIG. 6 a patch pocket stitched upon the coat either on the outside or it may be a pocket inside the lining of the coat is made extra long or deep, as indicated at 36 so that one inserting their hand into the pocket 36 would have to insert it a considerable distance in order to feel the purse 37. The pocket 36 includes an outer member 38 which is stitched at 39 inside the upper edge of the pocket 36 and to the pocket member 38. The flap, as indicated at 41 when returned to the pocket would fall into the bottom thereof. In other words the purse which is in a pocket 42 on the flap 41 will not have been rolled up to be accommodated in the pocket but its full flap 41 is generally equal in length to the pocket member 38. It can be seen that one trying to get to the pocketbook 37 would have to insert his hand a great distance in order to gain access to the lower edge of the flap 41 and lift it from the pocket 36.

In FIG. 7, a coat outer wall 45 has a lining 46. An outer pocket 47 is secured by the stitching 48 to the outer coat wall 45 to provide an upper edge 49 and this pocket 47 has inwardly thereof a pocket 51 that is stitched at 52 to the coat cloth 45 and in addition to having a main access opening 53 at the top thereof closed by an internal flap 54 stitched to the upper edge 49 of the outer pocket 47 by stitching 55 and closes an opening 56 that extends between the inner pocket 51 and the outer pocket 47. The present secret flap pocket 47 has a long flap 58 that is stitched at 59 to the upper edge 49 of the outer pocket 47. This flap 58 is at least the length of the outer pocket 47 and longer so as to extend through an opening 61 lying below the stitching 52 of the pocket 51 and between the pockets 47 and 51 into which the secret pocket 47 on the flap 58 can be extended. The opening 61 extends into a pocket formed by cloth material 62 extending between the

liner 46 and the cloth wall 45, and is attached by the same stitching 52 that the lower edge of the pocket 51 is stitched to the outer wall 45 of the coat. This pocket 62 is stitched at 63 to the outer wall 45 of the coat and provides for a pocket that will accommodate the long flap 58 bearing the purse 64.

If it is desired to have the purse, the long flap 58 will be pulled outwardly of the opening 56 at the top edges of the outer and inner pockets 47 and 51 which is covered by the flap 54. When returned the flap 54 provides a pocket 53 and the person attempting to seek the pocket purse 64 when the flap is within the garment would not because of this flap 54 be directed to the opening 56 and would not feel the purse 64 since it is carried in the inner pocket provided by the inner patch piece 62. Flap 58 and pocket 57 is returned through the opening 61 into the lining pocket.

In FIG. 8, there is shown a form of the invention in which double pockets 71 and 72 are provided on the outer side of coat cloth 73. An outer pocket piece 74 is in the form of a patch pocket and is stitched at the bottom and up the sides by a stitching 75. To the upper edge of this pocket there is secured a safety pocket flap 76 similar to the flap 58 of FIG. 7 and a small flap 77 adapted to cover an opening to the outer pocket 72 and be secured by snap members 78 to inner pocket wall 79 of the main pocket 71 which is also secured to the coat cloth 73 by stitching 81 that connects the pocket piece 79 at the bottom of the pocket 71 and up the sides thereof. With the flap 77 secured by the snap fasteners 78, no access is readily had to the outer pocket 72. The outer pocket piece 74, the secret pocket flap 76 and the small inner pocket flap 77 are secured together by a common stitching 82.

When it is desired to remove the flap 76, the small flap 77 is unsnapped and the flap 76 can be pulled outwardly out of the top of the pockets and this flap 76 is shorter than the flap 58 of FIG. 7 and only extends downwardly to the extend of the outer pocket 72 and itself has an opening 83 adapted to contain a purse or billfold 84. After the flap pocket 83 has been filled with the purse 84 or other valuable items, the flap 76 can be reinserted into the pocket 72 and the flap 77 snapped together by its snap fasteners 78.

In FIG. 9 there is provided a construction similar to the construction shown in FIG. 8, except the pocket for the flap is provided on the outside of the main pocket and closed by a short flap. In this form of the invention there is a main pocket 86 open at its upper edge and secured at its bottom and sides by a stitching 87 to coat wall 88. This constitutes the main pocket into which one would normally place articles, except the ones of a more valuable nature. To provide this secret pocket, an outer pocket piece 89 is secured over the main pocket piece by a stitching 91 that provides for an outer pocket 92 on the outer side of the main pocket. The upper edge of this outer pocket is below the outer edge of the main pocket 86 and to this outer or upper edge of the pocket 92 is secured by a safety pocket flap 93 by a stitching 94 and which in itself has a pocket 95 into which a billfold 96 may be dropped when the flap 93 is withdrawn from the pocket 92 extended over the edge of the outer pocket piece 89 and permitted to hang theredown with easy access to the pocket 95. Thereafter this flap 93 is lowered into the pocket 92

and a short flap 97 secured at its upper end to the upper edge of the pocket 86 by a stitching 98 can be lowered to close the pocket 92 and made secure by a button 99. One would normally enter the main pocket 86 and would not necessarily learn of the flap 93 containing the flap pocket 95. One would have to unbutton also the short flap 97.

Referring now, to the safety pocket construction of FIGS. 10 and 11, 101 represents a coat cloth onto which there is secured a patch outer pocket 102 formed of a cloth piece 103 that is secured by stitching 104 extending across the bottom and up the sides of the pocket. Inside the coat wall 101 is a safety flap pocket 105 secured to the coat cloth 101 by a stitching 106. This flap 105 has a pocket 107 into which a purse 108 is inserted. This pocket and the purse is thus contained wholly inside the coat cloth 101. In order to gain access to the flap and secret pocket, a slide fastener device 109 is used and when open as shown in FIG. 11 a flap 105 can be drawn outwardly so as to overhang the main pocket 102. The slide fastener when made open to withdraw the flap 105 provides an opening 110. It can be seen that the flap 105 can be readily reinserted through the opening 110 and the slide fastener closed so as to fully contain the flap 105 and its safety pocket 107 fully within the coat wall and inaccessible to one attempting to gain access to the purse by entering the main pocket 102. It should be seen that any slide fastener and the pulling outwardly of the flap pocket would require much exertion and by the time it was effected by one other than the wearer of the coat, the wearer of the coat would be well alerted.

It should also be apparent that the principle construction such as described in the simplest form of this invention of FIGS. 1 to 5, can be made use of in connection with ordinary inclined slant side pockets of trousers and with the other garments such as with breast pockets of coats, scarves, and money belts. The adaptation of this invention to these other garments will now be described.

In FIGS. 12 and 13, 115 represents trousers that are supported upon the wearer by a belt 116 and within which there is a slant side pocket 117 to which access can be had through a side opening 118. Connected to the upper end of the opening 118 is a puller flap 119 that has a secret pocket 120 into which a purse 121 can be inserted at its entrance point on the flap 119. With the purse inserted therein the flap 119 and its pocket 120 is folded and hinged or pivoted into the main pocket 117 as shown in 113. The opening entrance 122 will thus be inaccessible when this flap 119 is placed in the pocket. The main pocket 117 can be used free of this flap for any article of a less valuable nature. The length of the flap 119 in this instance is extra long and thus the flap should be rolled up before inserted into the pocket 117.

In FIGS. 14 and 15, a coat 125 is shown having a breast pocket 126 to the upper edge of which there is stitched to the outer pocket piece flap 127 that has a secret pocket 128 on its lower end and upon placing an article therein this flap or the pocket 128 can be rolled up as best seen in FIG. 15 and pivoted upwardly and tucked into the pocket without any access being readily had to the flap pocket 128.

In FIGS. 16 and 17, there is shown the secret pocket applied to a scarf 131 that normally has a main pocket 132 in one end thereof in which articles are normally placed. The scarf, of course, can be readily moved and this pocket can have ready access, and in order to prevent easy access to the articles, there is provided on this pocket 132 and adapted to hang from the upper edge thereof, a flap 133 containing a secret pocket 134 of itself into which articles can be disposed and the pocket 134 with the flap rolled up and inserted into the pocket 132 and in the manner as best illustrated in FIG. 17.

In FIGS. 18 and 19 there is shown the invention applied to a money belt 137 that can be tied about the body of the wearer with a notch 138 from which there hangs an apron portion 139 that in itself has a main pocket 141 for the carrying of various articles. In order to provide safety against easy removal from the money belt, a secret pocket flap 142 is secured to the upper edge of the pocket 141 and to the outer piece thereof and which can be pulled out of the pocket 141 and suspended as shown in FIG. 18 from the money belt 137 so that articles can be placed in the flap pocket 143. Thereafter, the flap pocket 143 and the flap 142 is rolled up and reinserted through the pocket opening 141 to be inaccessible within the pocket 141 and in the manner as shown in FIG. 19 and as described in connection with other forms of the invention.

FIGS. 20 and 21, there is shown another breast pocket assembly adapted particularly for spectacles, but which is similar to the vest pocket showing of FIGS. 14 and 15. According to this form of the invention, a coat 146 has a breast pocket opening 147 into the upper edge of the forward piece of the pocket opening 147 is secured a depending flap 148 having a secret pocket 149 into which spectacles 151 can be dropped, thereafter the pocket 149 and the flap 148 roll together and drop into the opening 147 of the breast pocket to thereby hold the spectacles against removal from the pocket unless the flap 148 and the pocket 149 is pulled outwardly therefrom. It should be seen that in the construction there is little opportunity for the spectacles to slide out of the pocket opening 147 and in this manner the glasses or spectacles are kept and concealed within the breast pocket so that other articles can be put into the breast pocket without the same interfering with the spectacles or would cause the spectacles to be pulled out of the pocket mistakenly.

It should be apparent now that there has been provided a secret pocket in such a way that the valuable articles are protected from easy removal from the main pocket. The articles are placed in a pocket provided on a flap and the flap can be withdrawn from the pocket opening when desired in a manner unfamiliar to one normally making use of a main pocket in the garment of a wearer.

While various changes may be made in the detailed construction, it shall be understood that such changes shall be within the spirit and scope of the present invention as defined by the appended claims.

What is claimed is:

1. A garment having a main pocket with an upper edge, a flap secured to the upper edge of the pocket and adapted to be normally carried within the pocket but removable over the upper edge thereof to depend

therefrom, said flap having a pocket lying on the inner side and adjacent the lower end thereof as it is suspended outwardly from the upper edge of the main pocket and adapted to receive a purse or other valuable item, said flap being in length substantially longer than depth of the main pocket, an inner pocket lying on the garment inwardly of the garment wall extending downwardly from the bottom of the main pocket, said garment wall having a slit opening extending from the bottom of the main pocket into the upper end of the inner pocket, said flap being extendable through the slit opening into the inner pocket locate its purse carrying

10 pocket therewithin and removed from the main pocket to secret its contents.

5 2. A garment as defined in claim 1 and a further inner pocket lying on the outer side of the garment wall and within the main pocket and extending upwardly adjacent the upper edge of the main pocket, said flap being extendable between the inner and main pockets and a closure flap attached to the upper edge of main pocket and extendable downwardly over the inner pocket thereof.
